GUN AND GUNNER'S CHAIR MOUNTING

James S. Smithson, Beverly Hills, Calif., assignor
to Douglas Aircraft Company, Inc., Santa
Monica, Calif., a corporation of Delaware

Application May 4, 1934, Serial No. 723,909

16 Claims. (Cl. 89—37.5)

1

My invention relates to gunnery and comprises generally a gunner's chair having novel features including a supporting structure upon which the chair and a gun are mounted, the supporting structure, the chair, and the mounting for the gun providing novel means of adjustment enabling the gunner to cover a maximum field of fire while seated comfortably in the chair.

My invention is adapted for use in combination with rapid fire guns such as machine-guns, and particularly with the so-called flexible type machine-guns.

While my invention is adapted for immobile use, such, for instance, as in a trench, in anti-aircraft service, or in a machine-gun nest, it is particularly suited for use in combination with some form of carrier, such as an airplane, tank, motor car, or speed boat. The invention finds an important use in combination with an airplane, and therefore will be described in connection with an airplane in the following part of the specification, and will be illustrated in connection with an airplane in the accompanying drawings.

In military airplanes, flexible machine-guns, when used, are ordinarily positioned in a rear cockpit in the fuselage, or, in certain types of planes, in a cockpit in the forward end of the fuselage ahead of the wings.

The gunner usually has other duties to perform, such as those of a radio operator, photographer, or bomber, as well as handling landing flares and flares for determining wind drift, etc. The numerous equipment just referred to, together with the machine-gun, must be placed within the gunner's cockpit, in various positions forward and aft and at the sides of the seat occupied by the gunner.

The violent maneuvers of a modern high performance airplane in combat make it extremely hazardous for the gunner unless he is at all times securely strapped to the ship.

It is therefore an object of my invention to provide a gunner's chair in which a gunner may be securely strapped at all times and which is movable to permit the gunner to face aft while operating the flexible gun, and to face forward for access to radio equipment, auxiliary flight controls, or other equipment, without the necessity of unstrapping himself from the plane and standing in the cockpit to make the change.

It is another object of the invention to provide a gunner's chair, permitting the gunner to remain comfortably seated and securely strapped to the ship while operating a flexible machine-gun throughout its complete range of fire.

It is a further object of my invention to provide a supporting structure for a gunner's chair and a flexible machine-gun, upon which the chair and gun are so movable that a maximum range of

5 fire is obtained from the rear cockpit of a plane, from substantially straight overhead to downward and forward to the trailing edge of the lower wing on either side of the fuselage, and enabling the gunner without changing his normal sitting position in the chair to cover with facility the entire area between these limits with the exception of the space blanketed off by the empennage and fuselage.

10 It is another object of my invention to provide a gunner's chair including a supporting structure upon which a gun carriage and a chair are so movably mounted that a gunner strapped in the chair in a normal sitting position may face in any direction forward or aft of the plane without unstrapping himself from the chair and thus follow the movement of the gun throughout its entire range of fire, the supporting structure being pivotally supported so that the chair and gun carriage may be tilted together to increase the overhead range of fire and to allow the gunner to be comfortably and safely secured to the ship while firing directly overhead.

15 It is another object of my invention to provide in combination with a gunner's chair, as described in the above paragraph, a seat which is adjustable relative to the frame of the chair so that the gunner seated thereon may at will raise the seat relative to the gun carriage so as to obtain a maximum downward angle of fire over the sides of the fuselage of the plane.

20 It is another object of my invention to provide in combination with a device as described above, an airplane providing a means for housing the machine-gun within the contour of the fuselage when not in use, to minimize drag.

25 It is another object of my invention to provide a gun carriage including means for moving the gun from the inoperative position within the contour of the fuselage into a raised operating position.

30 These and other objects will be made apparent in the following part of the specification, the accompanying drawings, and the appended claims.

35 In the drawings,

40 Fig. 1 is a side elevation of my device, with fragmentary portions of the frame structure of an airplane being shown to illustrate the manner of connecting the device therewith, and showing a machine-gun associated with the device supported in an inoperative position within an enclosing recess formed in the fuselage of the plane, and showing the gunner's chair facing forward.

45 Fig. 2 is a view comparable to Fig. 1 but showing the machine-gun supported by the device in a raised, operative position above the body or fuselage of the plane, and showing the gunner's chair facing aft in the direction in which the machine-gun is trained.

50 Fig. 3 is a view comparable to Figs. 1 and 2,

but showing the gunner's chair tilted into a substantially reclining position and showing the machine-gun trained substantially straight above the gunner's chair.

Fig. 4 is a plan view of the device with the machine-gun removed to more clearly show the gun carriage of the device, and showing the carriage and gunner's chair pivoted into different positions from the positions in which they are shown in Figs. 1 and 2.

Fig. 5 is a vertical section through the device, taken as indicated by the line 5—5 of Fig. 2.

Fig. 6 is an enlarged sectional view through the gun carriage of the invention, taken as indicated by the line 6—6 of Fig. 4.

Figs. 7 and 8 are horizontal sections through the gun carriage, taken as indicated by the lines 7—7 and 8—8 respectively of Fig. 6.

Fig. 9 is a fragmentary elevation of a portion of the gun carriage, taken as indicated by the line 9—9 of Fig. 8.

Fig. 10 is a fragmentary view partly in section of the mechanism for supporting and locking the seat of the chair upon the frame thereof, this view being taken as indicated by the line 10—10 of Fig. 5.

Fig. 11 is an enlarged fragmentary section, taken as indicated by the line 11—11 of Fig. 4.

Fig. 12 is an enlarged fragmentary section, taken as indicated by the line 12—12 of Fig. 4.

Fig. 13 is an enlarged fragmentary elevation of that portion of the device located within the dot and dash line x in Fig. 1.

Fig. 14 is a sectional view illustrating the tilting control latch of the device, this view being taken as indicated by the line 14—14 of Fig. 2.

Referring at first to Figs. 1 and 2, I will first generally designate the elements comprising the fundamental combination of the invention as follows: a supporting structure 12, a chair 13, and a gun carriage 14 having a machine-gun 15 mounted thereon. One concept of the invention includes in combination a carrier body, such as the fuselage of an airplane, which for illustrative purposes is indicated in Figs. 1, 2, and 3 of the drawings in dot and dash lines and by fragmentary portions of the frame thereof indicated in solid lines, and which will be referred to later. My invention also embraces, however, the combination of the fundamental elements of the invention with other forms of carrier, mentioned above, which for simplicity it is not deemed necessary to illustrate.

Referring now to the pertinent details of construction and with reference at first to Figs. 1 to 4, inclusive, the supporting structure 12 comprises an annular ring 16 which provides a chair track, which supporting structure is pivotally secured on its transverse axis by pivots 17, to a pair of brackets 18 which are in turn supported by the frame forming the walls of the fuselage of an airplane indicated at 20 in Figs. 1, 2, and 3. I prefer to pivot the track 16 to the brackets 18 by pivot members 17, of the character best shown in Fig. 12, each of which includes bolt and nut means 19, extending through bearing means 21, consisting of a bushing 21a and a wear washer 22, substantially in the manner shown. The pivots 17 serve to pivotally mount the supporting structure 12 on an axis designated in Figs. 1 to 4 inclusive by the letter A and which will be hereinafter called the primary or tilting axis. The primary axis A, in the present instance being illustrated in connection with an airplane fuselage, preferably extends in a horizontal plane

transversely of the longitudinal axis of the fuselage.

The annular ring 16 which provides the chair track is provided with substantially flat upper and lower surfaces 25 and 26 in which are respectively formed continuous grooves 27 and 28 for the reception of friction reducing means included in the chair structure 13 which I will now describe.

10 The chair 13 comprises generally a frame 30, a back structure 31, and a seat 32. The frame 30 is formed of a pair of parallel tubular or cylindrical posts 35 rigidly connected together at the bottom thereof by a spacer 36 having a clamp member 37 welded or otherwise secured at each end thereof, which clamp members are adapted to be clamped to the lower ends of the posts 35 by suitable bolt or rivet means 38.

The upper ends of the posts 35 are rigidly secured together and are relatively spaced by the back structure 31 which comprises, as best shown

in Figs. 1, 4, and 5, a substantially semicircular back rest 40. Secured to the back rest 40 are a pair of hanger members 41 and 42, and a plurality of auxiliary hangers 60.

Each of the hanger members 41 and 42 provides a substantially C-shaped body 44 providing a vertical wall 45, upper and lower horizontal walls 46 and 47 respectively, and upper and lower vertically extending

lips 48 and 49. Formed on the vertical wall 45 are upper and lower bosses 50, respectively, cooperating with the lips 48 and 49 to support bearing members 51 adapted to journal friction reducing

means in the form of upper and lower rollers 52 and 53 provided to engage the upper and lower

grooves 27 and 28 formed in the track member 16. The hanger members 41 and 42 are rigidly secured to opposite ends of the semi-circular back

rest 40 by rivets 55 or other suitable means. Preferably the C-shaped bodies 44 of the hanger members 41 and 42 are positioned so as to curve around the inner surface of the track 16, and the back rest 40 is secured thereto, substantially in the

manner shown in Figs. 4 and 5, so that a smooth inner surface is provided, obviating the possi-

bility of the clothing of an occupant becoming caught between the rollers and the track. The body 44 of each of the hangers 41 and 42 is pro-

vided with a downwardly extending cylindrical

portion 58 adapted to receive the upper end of

one of the posts 35, to which it is rigidly secured in any suitable manner, such as by rivets indi-

cated at 59 in Figs. 4 and 5.

In order to provide additional rigidity of the

55 chair structure, I secure a plurality of auxiliary hangers 60 spaced about the semicircular back

rest 40 as best shown in Fig. 4. Referring par-

ticularly to Fig. 11, each of the auxiliary hangers

comprises a substantially C-shaped body 61, simi-

lar to the body 44 of the hangers 41 and 42,

providing a vertical wall 62, upper and lower

horizontal walls 63 and 64, and vertically extend-

ing lips 65 and 66 cooperating with bosses 67 and

68 in forming supports for bearing members 69

journalling rollers 70 which engage the upper and

lower track grooves 27 and 28 of the track 16.

Similar to the hanger members 41 and 42, the

C-shaped bodies of the auxiliary hangers are posi-

tioned to curve around the inner surface of the

track 16 and are secured, preferably in the man-

ner shown in Fig. 11 to the back rest 40, by the

screws comprising the bearing members 69, so

that the back rest presents a smooth inner sur-

face.

75 The hanger members 41 and 42 and the

auxiliary hangers 60 cooperate to movably support the chair structure on the supporting structure or track 16. It will be seen that the rollable engagement of the hangers with the track pivots the chair structure 13 about the central axis of the track 16, designated by the letter B in Figs. 2, 3, and 4, moving the chair structure 13 in an arcuate path about this axis. The axis B, which I will hereinafter call the secondary or pivoting axis, is preferably substantially perpendicular to the primary axis A.

Coming now to the specific construction of the seat 32 with reference to Figs. 1 to 5 inclusive and to Fig. 10, the seat proper may be of any desired type or construction suitable for the particular use to which the invention is subjected. In the present form adapted for combination with an airplane, I prefer to use a seat of the type illustrated in the drawings, which is designed to accommodate a standard seat-type parachute.

Secured to each side of the seat 32 is a tubular member 65 slidably positioned on one of the posts 35 of the chair frame 30. The manner of securing the members 65 to the seat is immaterial, but might conveniently include a pair of laterally extending wings 66 on each side of the seat, between which a pair of spaced lugs 67 on each of the members 65 is secured, as by bolts 68. The tubular members 65 are freely slidable on the posts 35 to move the seat 32 along the longitudinal axis of the frame 30, thus varying the distance between the seat 32 and the track 16 of the supporting structure 12. The downward movement of the members 65, and thus the seat 32, is limited by the clamp members 37.

My invention includes means for supporting and locking the seat selectively in various positions along the longitudinal axis of the frame 30. One form of mechanism for accomplishing this purpose includes plunger means 70, movable with the seat and resiliently engageable with a series of drilled holes or depressions 71 located at spaced intervals along the posts 35. The preferred form of seat locking mechanism comprises, as best shown in Figs. 4, 5, and 10, a horizontally extending rod 72 journaled by bearing brackets 73 across the front of the seat 32, to each end of which is secured a depending lever 74, the lower end of each lever being pivoted to a plunger rod 70 extending through a plunger box 75 formed on each of the members 65 at right angles to the posts 35 of the chair frame 30. Provided, in spaced relationship on each of the posts 35 are a series of drilled holes 71, into one of which each of the plunger rods 70 extends. Positioned around each of the plunger rods 70 within its respective plunger box is a compression spring 76 which is compressed between the outer end of the box and a washer 77 fixed longitudinally on the plunger rod by a pin 78 for the purpose of resiliently urging the plunger rod into a hole 71 in its respective post 35. If desired, guide means for keeping the plunger rods 70 at the desired angle relative to the posts 35 may be provided in the form of an auxiliary wall 78a within each of the plunger boxes 75 having a central hole therein in which the plunger rod is slidable.

Provided on the horizontal rod 72 is an outwardly projecting U-shaped handle 80 positioned to be conveniently grasped by an occupant seated in the chair 13. The handle 80, the rod 72, and the lever 74 operate as a crank means when the handle is pulled upwardly to withdraw the plunger rods 70, against the resilient action of the springs 76, from engagement with the holes

71, permitting the seat 32 to slide freely relative to the chair frame 30.

The preferred form of the invention includes means for automatically raising the seat 32 when the plunger rods 70 are released from engagement with the holes 71 to obviate the necessity of the occupant manually raising the seat after it is unlocked. This I accomplish by providing suitable resilient means between the seat 32 and the frame 30 urging the seat upwardly.

One convenient form of resilient means for accomplishing this purpose is shown in Figs. 1, 2, 3, and 5 and includes a pulley 85 journaled on a stub shaft 83 projecting laterally from the outer side of each of the hanger members 41 and 42. Projecting outwardly from each of the slide members 65 of the chair 32 is an ear 87. Secured to each of the ears 87 in any suitable manner is a cord 88 of suitable resilient material, these cords extending upwardly over the pulleys 85 thereabove and then extending downwardly to be secured to the lower part of the frame 30, for instance, by eye-bolts 89 secured to the clamps 37, substantially as shown.

Coming now to a description of the gun carriage 14, movably supported on the supporting structure 12, I show a gun track 95 which is preferably substantially semi-circular and which is secured to a section of the chair track 16 by blocks 96 and a bracket 97, and upon which the gun carriage 14 is movable in a manner which I will describe in detail later. In the form of the invention illustrated, the gun track 95 extends around the aft section of the chair track 16; that is, toward the back end of the airplane, and the gun carriage moves on the track 95 independently of the chair in an arcuate path adjacent to the chair 13.

Referring to Figs. 1 and 6, the gun track 95 preferably comprises a vertical wall 98 of semi-circular form and having upper and lower tri-surfaced rails 100 and 101 formed integrally thereon. The upper rail 100 is formed to provide an upwardly facing horizontal surface 102 and inner and outer vertical surfaces 103 and 104, all of these rail surfaces being symmetrical with the semicircular form of the wall 98 throughout its length. The lower rail 101 is formed similar to the upper rail but inverted to provide a downwardly facing horizontal surface 105 and inner and outer vertical surfaces 106 and 107.

The gun carriage 14 provides a body 110 providing upper and lower horizontal walls 111 and 112 relatively spaced to respectively extend over and under the gun track 95. Depending from the upper wall 111 is a pair of relatively spaced stub shafts 115 positioned with respect to the track 95 so that friction reducing elements in the form of rollers 116 journaled theron will engage the inner vertical surface 103, as best shown in Figs. 6 and 7. Also depending from the upper wall 111 is a pair of relatively spaced stub shafts 120, positioned so that rollers 121 journaled thereon engage the outer vertical surface 104. Formed on the body 110 on each side thereof adjacent the upper wall 111 is a vertically extending lug 122, each suitably supporting a stub shaft 123 upon which is journaled a roller 124. The rollers 124, as best shown in Fig. 7, are relatively spaced a considerable distance apart and are positioned to roll upon the horizontal surface 102.

Extending upwardly from the lower horizontal wall 112 are stub shafts 127 and 128 positioned symmetrically with the stub shafts 115 and 120, and journaling pairs of rollers 129 and 130 re-

spectively engaging the inner and outer vertical surfaces of the lower rail 101. Formed on the body 110 on each side thereof adjacent the lower wall 112 is a vertical lug 131, these lugs supporting stub shafts which journal rollers 132 engaging the downwardly facing surface 105 in positions symmetrical with the rollers 124.

It will be clear that the rollers described above which engage the upper and lower rails 100 and 101 of the track 95 comprise a friction reducing means movably supporting the carriage on the track. It is to be understood, however, that my invention contemplates other means of supporting the carriage for movement on the track.

Pivoted between a pair of lugs 140 formed on the lower part of the body 110 is a gun standard 141. The standard 141 is pivoted to swing in a vertical plane disposed centrally of the body 110 as indicated by the dotted line D—D of Fig. 7.

Formed in the body 110 is a gun standard seat comprising a longitudinally extending semicircular groove 145 adapted to receive the body 146 of the standard 141 when it is swung into a substantially vertical position. The body 146 of the standard 141 is preferably cylindrical and the upper portion 147 of the groove 145 is formed to fit tightly therearound. Provided on the body 110 adjacent the upper end of the groove 145 is a pair of vertically disposed wings, adapted to pivotally support a latch member 148 on a pin 149. The latch member 148 is provided with a dog 150, projecting outwardly over the groove 145 and is also provided on the opposite end thereof with a thumb piece 151. A spring 152 is associated with the latch member substantially in the manner shown so that the dog 150 is resiliently depressed thereby, the downward movement thereof being limited by suitable stop means 153 of any desired form.

Formed in the body 146 of the gun standard 141 is an opening 155 comprising engagement means whereby the latch member is operable to lock the gun standard rigidly to the gun carriage when the standard is raised into its vertical position.

Provided on the upper end of the gun standard 141 is a connecting device indicated at 160 which may be of any desired type suitable for releasably connecting with the universally pivoted trunnion of a standard flexible machine-gun, such as the gun 15 illustrated in the drawings.

My invention also provides means for selectively locking the gun carriage in various positions in its arcuate path of travel. One form of mechanism for accomplishing this purpose includes a series of holes or depressions 162 provided in the wall 98 and extending substantially the entire distance around the semicircular track in relatively spaced relationship as indicated in Figs. 1, 2, and 3. Pivotedly supported on a horizontal shaft 163 extending between bosses 164 formed on the body 110 of the carriage 14 is a plunger means in the form of a depending lever 165 having a pin 166 projecting therefrom adapted to engage one of the series of holes 162. Resilient means for urging the plunger pin into the holes 162 is provided in the form of compression springs 167 positioned between the lever 165 and the carriage body 110. As shown best in Fig. 9, the lever 165 is preferably formed of sufficient width to allow one of the springs 167 to be positioned on each side thereof and at the same level as the plunger pin 166 to prevent any tendency the lever might have to twist relative to the shaft 163. Spring retaining means in the form

of pins 168 around which the springs 167 are coiled may be threaded into the body 110 of the carriage as shown, and if so desired, the pins may extend outwardly through openings 169 in the lever 165, these openings being sufficiently enlarged to allow the pivotal movement of the lever without binding on the pins 168.

For actuating the plunger 166 to release the carriage for free movement on the track 95 it is preferable to provide an operating handle 170 which is readily accessible to either hand of the gunner while he is operating the gun. With this in view, I prefer to provide an operating handle comprising a pair of arms 171 and 172, each of which is secured to the hub portion 173 of the lever 165 in any suitable manner so as to pivot therewith on the shaft 163. The arms 171 and 172 are curved upwardly around and over the upper rail 100 of the track, extending through elongated slots 174 and 175 formed for this purpose in the upper horizontal wall 111 and then extending a considerable distance toward the chair structure 13, as best shown in Figs. 4 and 6. After curving upwardly through the slots 174 and 175 the arms 171 and 172 are preferably bent laterally to increase the space therebetween so that a relatively long grasping handle 176 may be secured between the outer ends thereof, substantially in the manner shown in Fig. 4.

In order to obviate the necessity of the gunner using either hand to operate the handle 170, I provide on the machine-gun 15 a cam 180 located in such a position that when the gun standard 141 is in its raised operating position, as shown in Figs. 2 and 3, the cam will contact the handle portion 176 of the operating handle when the butt of the gun is pivoted downwardly as indicated in Fig. 3.

My invention includes means for locking the supporting structure 12, which in this instance includes the chair track 16 and the gun track 95, in the various positions into which it is tilted between the normal position illustrated in Fig. 2, into the substantially reclining position illustrated in Fig. 3.

The preferred form of lock means is illustrated as comprising a pair of telescoping tubes 190 and 191, the inner one of which is pivotally secured to the supporting structure, preferably to the bottom of the bracket 97, by pin or bolt means 192, and the outer one of which is pivoted at the lower end thereof to a bracket 193 secured to the floor or other suitable part of the frame structure forming the fuselage of a plane, substantially in the manner shown.

As best shown in Fig. 14, the outer tube 191 is provided with an opening through one side wall thereof, which communicates with a laterally extending cylinder 195, having an outer end wall 196 provided with a central opening. Slidable in the cylinder 195 is a plunger 197 having a pin 198 secured thereto, which pin extends outwardly through the opening in the end wall 196. Secured to the tube 191 below the cylinder 195 is a bracket 199 pivotally supporting, as by pin or bolt means 199a, an operating lever 200. The upper portion of the lever 200 extends parallel with the tube 191 and is provided at the upper end thereof with a fork 201 through which the pin 198 extends. A nut and washer 202 or other means forming an enlarged head are provided on the extreme outer end of the pin 198 and are engageable by the fork 201. The lower end of the lever 200 is curved substantially as shown in Figs. 4 and 14 so as to be engageable by the foot.

of the occupant. Resilient means is provided to force the plunger 197 into one of a series of relatively spaced holes 204 in the inner tube 190 in the manner illustrated in Fig. 14 for the purpose of locking the tubes 190 and 191 against relative movement and thus locking the supporting structure in a position dependent upon the adjustable length of the telescoping tubes. As indicated in Fig. 14, the resilient means just referred to may be in the form of a spring 205 located in the cylinder 195 and compressible between the plunger 197 and the outer wall 196 of the cylinder.

In the preferred form of the device the lower end of the tube 190 is closed by a wall 206 having a central opening therein through which extends a stop rod 208. The lower end of the stop rod is secured in fixed relationship with the outer tube 191 in any suitable manner and the upper end thereof is provided with an enlarged head portion 209 adapted to engage the wall 206 to limit the elongation of the telescoping tubes and thus the backward inclination of the seat structure 13. A suitable stop member 210 is also provided in the lower end of the tube 191 to limit the collapsing of the tubes and thus determine the normal plane of the supporting structure and the normal position of the chair structure.

A chair lock generally designated by the numeral 215 is also provided in the device for preventing, when desired, the movement of the seat on the track 16. As shown best in Fig. 13, the lock 215 comprises a cylinder 216 secured to one of the hanger members, such as the hanger 42, in a position adjacent and at right angles to the lower surface of the track 16. Slidable in the cylinder 216 is a lock bar 217 manually movable by means of a handle 218 projecting laterally therefrom through a longitudinal slot 219 formed in the wall of the cylinder 216. The lock bar 217 is resiliently urged upward to force the upper end 220 of the bar into engagement with a drilled hole 221 in the track 16 by a compression spring 222 confined between a shoulder 223 on the bar 217 and a shoulder 224 formed in the cylinder. Formed as a continuation of the lower end of the slot 219 there is provided a lateral slot 225 into which the handle 218 may be moved by a rotation of the bar, after it has been depressed, to hold the portion 220 of the bar out of engagement with the hole 221. Other holes 221 may be provided at various positions on the track 16 to lock the chair 13 against rotation if desired.

The operation of the gunner's chair in its various uses is as follows. When installed in the fuselage of an airplane as above described, the chair is ordinarily positioned as shown in Fig. 1, facing toward the front of the plane indicated by the arrow E. Ordinarily when facing in this position the occupant has access to equipment, such as radio, photographic apparatus, etc.

When the machine-gun 15 is not in use, the gun standard is swung rearwardly and downwardly to lower the gun into an inoperative position within a recess 230 formed in the top of the fuselage adjacent the cockpit and extending longitudinally of the fuselage. The recess comprises vertical side walls 231 and a bottom wall 232, these walls being supported by suitable framework which in turn is supported by the framework 233 of the fuselage. When the gun 15 is lowered into the recess within the contour of the fuselage wind drag is reduced to a mini-

mum and the machine-gun is not in the way of the occupant of the chair. Suitable latch means indicated at 235 is preferably provided to securely support and lock the gun in this position. As shown, the latch means may be secured to a cross member of the frame 233 and is preferably of the automatic latch type having a manual releasing member 236.

When it is desired to fire the machine-gun the gunner releases the chair lock 215 in the manner above described, which allows the chair to freely pivot through 360° about the secondary axis B and allows the gunner to turn facing aft toward the gun without changing his normal sitting position and while remaining securely strapped to the chair. The gunner then actuates the releasing member 236 to release the latch means 235 and pulls forwardly on the handles of the gun as indicated by the arrow F in Fig. 1. The gun standard 141 pivoting at the lower end thereof swings upwardly into a vertical position within the groove 145 and is locked rigidly to the gun carriage by the latch dog 150.

The gun 15 may then be moved around the track 95 and locked in any desired position without the gunner removing his hands from the gun, it being only necessary for the gunner to tilt the butt of the gun sharply downward, move the carriage in any direction, and then raise the gun to allow the plunger 166 to engage one of the holes 162, which locks the carriage in the new position. It is, of course, obvious that the gunner may at all times follow the movement of the gun, so that he faces in the direction of aim, by reason of the free pivotal movement of the chair on the track 16.

When the gunner desires to change the angular position of the chair so that the chair tilts backwardly from the normal sitting position into a reclining position in order to cover a field of fire directly above the plane, as indicated in Fig. 3, he depresses the lever 200 with his foot, as indicated by the arrow G. The resultant pivoting action of the lever withdrawing the plunger 197 from engagement with the holes 204, allows the chair to be tipped backwardly into whatever angular position the gunner desires and to be locked in this position by permitting the plunger 197 to engage another of the holes 204.

In order to facilitate the use of the foot lever 200 and to increase the ease with which the gunner may tilt and pivot the chair 13 to follow the movement of the gun 15, it is preferable to provide stirrups 240 in which he may place his feet, the stirrups being mounted on the frame of the fuselage in any desired manner.

In order to obtain a maximum athwartships and downward angle of fire over the side of the fuselage, the gunner pulls upwardly on the seat lock handle 80, as indicated by the arrow H, thereby withdrawing the plunger 70 from engagement with the hole 71. The gunner then rises and the seat 32, being urged upwardly by the resilient cords 88, rises easily without appreciable effort on the part of the gunner. The release of the handle 80 when the desired height of the seat is attained locks the seat in the upward position. To lower the seat the gunner merely pulls the handle 80 with one hand and the seat sinks, the resilient cords 88 preventing a too rapid or violent fall thereof.

It will be noted in the form of the invention disclosed that the primary axis A, the secondary axis B, and the axis about which the gun carriage moves in its arcuate path are relatively off-

set. It should be understood that this disclosure is merely a style of design and that the axes A and B might intersect and the gun carriage might be pivoted on the axis B without changing the relative functions of the elements comprising the fundamental combination which I claim as my invention. It should also be understood that I am aware of numerous other changes that might be made in the device disclosed and of numerous other embodiments thereof that might be devised without changing the spirit and scope of my invention, which should be interpreted by the appended claims.

The term "bodily movable" as employed herein is used to distinguish from a pivotal movement and refers to a movement of the mass or body as a whole or in its entirety rather than a movement around a fixed axis extending through a mass or body.

I claim as my invention:

1. In a device of the character described, the combination of: a supporting structure; a chair movable on said structure so that the occupant may face in different directions in a normal sitting position; carriage supporting means on said supporting structure; a gun carriage adapted for mounting a gun; means for mounting said gun carriage on said carriage supporting means so that said gun carriage is bodily movable in a path about said chair; and means for pivotally supporting said structure to tilt said chair from said normal position into a substantially reclining position.

2. In a device of the character described, the combination of: a supporting structure including an arcuate chair track and a gun carriage track; a chair movable on said chair track; a gun carriage adapted for mounting a gun movable on said gun carriage track in an arcuate path adjacent to and independently of said chair; and means for pivotally supporting said supporting structure to tilt said chair and said carriage into different positions.

3. In a device of the character described, the combination of: a supporting structure; an arcuate gun track supported by said structure; a gun carriage movable on said track; a chair supported by said structure and movable thereon so that the occupant may face in different directions to follow the movement of said gun carriage; means for mounting a gun on said gun carriage; lock mechanism including plunger means resiliently mounted on said carriage adapted to engage stop means on said track for locking said carriage in various positions on said track; and cam means mounted on said gun and operable by a movement of said gun to actuate said lock mechanism to release said carriage for movement on said track.

4. In a device of the character described, the combination of: a supporting structure; a gun carriage adapted for mounting a gun; a carriage supporting means on said structure whereby said gun carriage is bodily movable on said structure in an arcuate path; a chair including a frame and a seat supported by said structure and movable thereon independently of said gun carriage so that the occupant may face in different directions to follow the movement of said gun carriage; means for pivotally supporting said structure to tilt said chair and said carriage; and means for releasably locking said seat to said frame in different positions.

5. In a device of the character described, the combination of: a supporting structure; a gun carriage movable on said structure; a chair mov-

able on said structure so that the occupant may face in different directions; means for pivotally supporting said structure to tilt said chair and said carriage; and a gun standard pivoted to said carriage and operable to swing from an upright position in which it supports a gun in an operative position into an inclined position away from said carriage to lower said gun into an inoperative position.

10 6. In a device of the character described, the combination of: a supporting structure; a gun carriage movable on said structure; a chair movable on said structure so that the occupant may face in different directions; means for pivotally supporting said structure to tilt said chair and said carriage; a gun standard pivoted at the lower end thereof to the lower part of said carriage; and means for releasably locking the upper end of said standard to said carriage to rigidly secure said standard thereto in an upright position in which it supports a gun in an operative position, said standard pivoting when released to move said gun into an inoperative position.

15 7. In a device of the character described, the combination of: a supporting structure; a gun carriage; a carriage supporting means on said structure whereby said gun carriage is bodily movable on said structure in an arcuate path; a chair supported by said structure and movable thereon independently of said gun carriage so that the occupant may face in different directions to follow the movement of said gun carriage; and means for pivotally supporting said structure to tilt said chair and said gun carriage forwardly and backwardly.

20 8. In combination with a machine-gun: a gun carriage having a gun-standard seat; means for movably supporting said carriage; an elongated gun standard pivoted at the lower end thereof to the lower part of said carriage; and means for releasably locking the upper end of said standard to said carriage to rigidly secure said standard in said seat in an upright position operatively supporting said gun, said standard pivoting when released to move said gun into an inoperative position.

25 9. In combination with an airplane providing a body: walls forming a recess within the contour of said body; a gun carriage; means for movably supporting said gun carriage adjacent said recess; an elongated gun standard pivoted at the lower end thereof to said carriage; and means for releasably locking the upper end of said standard to said carriage to rigidly secure said standard thereto in an upright position operatively supporting said gun above said body, said standard pivoting when released to move said gun into an inoperative position within said recess.

30 10. In combination with an airplane providing a body: walls forming a recess within the contour of said body; a gun carriage; means for movably supporting said gun carriage adjacent said recess; an elongated gun standard pivoted at the lower end thereof to said carriage; means for releasably locking the upper end of said standard to said carriage to rigidly secure said standard thereto in an upright position operatively supporting said gun above said body, said standard pivoting when released to move said gun into an inoperative position within said recess; and means for releasably locking and supporting said gun in said recess.

35 11. In a device of the character described, the combination of: a supporting structure; a ring

40 45 50 55 60 65 70 75

13

pivots mounted in said supporting structure so as to tilt about an axis substantially perpendicular to the axis of the supporting structure; a seat structure rotatably mounted on said ring; means for locking said seat in any position of rotation about the center of the ring; means for adjusting said seat vertically with respect to the ring; means for locking said seat at various heights; a substantially annular track fixed to the ring to tilt therewith; a carriage mounted on said track movable on said track; means on said carriage for carrying a machine gun; means for moving the gun substantially downward and to the rear to an inoperative position; and means for locking said gun in both operative and inoperative positions.

12. In a device of the character described, the combination of: a supporting structure; a chair movable on said structure so that the occupant may face in different directions; a gun carriage adapted for mounting a gun; a track on said structure on which said gun carriage is movable; and means for pivotally supporting said supporting structure so that said chair and said carriage may be tilted together.

13. In a device of the character described, the combination of: a supporting structure; a chair movable on said structure so that the occupant may face in different directions; a gun carriage track on said supporting structure; a gun carriage adapted to carry a gun mounted on said track and movable thereon; and means for pivotally supporting said supporting structure so that said chair and said gun carriage may be tilted together.

14. In a device of the character described, the combination of: a supporting structure; a chair movable on said structure so that the occupant may face in different directions; a gun carriage track on said supporting structure; a gun carriage mounted on said track and movable thereon, said gun carriage having a pivotal support for a gun; and means for pivotally supporting said supporting structure so that said chair and said gun carriage may be tilted together.

15. In a device of the character described, the

14

combination of: a supporting structure; a chair movable on said structure so that the occupant may face in different directions, said chair having a seat and means whereby said seat may be independently raised or lowered; a gun carriage track on said supporting structure; a gun carriage adapted to carry a gun mounted on said track and movable thereon; and means for pivotally supporting said supporting structure so that said chair and said gun carriage may be tilted together.

5 16. In a device of the character described, the combination of: a supporting structure; an arcuate gun track supported by said structure; a gun carriage movable on said track; means for mounting a gun on said gun carriage; lock mechanism including plunger means resiliently mounted on said carriage adapted to engage stop means on said track for locking said carriage in various positions on said track; and cam means 15 mounted on said gun and operable by a movement of said gun to actuate said lock mechanism to release said carriage for movement on said track.

20 25 17. In a device of the character described, the combination of: a supporting structure; an arcuate gun track supported by said structure; a gun carriage movable on said track; means for mounting a gun on said gun carriage; lock mechanism including plunger means resiliently mounted on said carriage adapted to engage stop means on said track for locking said carriage in various positions on said track; and cam means mounted on said gun and operable by a movement of said gun to actuate said lock mechanism to release said carriage for movement on said track.

JAMES S. SMITHSON.
